CLAIM

The ornamental design for a bean bag toss game, as shown.

DESCRIPTION

FIG. 1 is a top plan view of a bean bag toss game showing my new design in closed position;

FIG. 2 is the bottom plan view thereof;

FIG. 3 is a side elevation view thereof, the opposite side being a mirror image;

FIG. 4 is the rear elevational thereof;

FIG. 5 is a front elevational view thereof; and,

FIG. 6 is a perspective view showing the claimed design in an open position.
